UNITED STATES PATENT OFFICE.

JOHN WICKS, OF CHICAGO, ILLINOIS, ASSIGNOR TO AUTOMATIC ELECTRIC COMPANY,
OF CHICAGO, ILLINOIS, A CORPORATION OF ILLINOIS.

SEMIAUTOMATIC TELEPHONE SYSTEM.

REISSUED

1,404,416.

Specification of Letters Patent. Patented Jan. 24, 1922.

Application filed March 4, 1918. Serial No. 220,151.

To all whom it may concern:

Be it known that I, JOHN WICKS, a citizen of the United States of America, and a resident of Chicago, Cook County, and State 5 of Illinois, have invented certain new and useful Improvements in Semiautomatic Telephone Systems, of which the following is a specification.

My invention relates in general to improved circuits and apparatus for use in a semi-automatic telephone system in which automatic switches are controlled either automatically by a subscriber or through the medium of an operator to establish connections.

More specifically, my invention relates to means whereby in such a system, when a call is made from a subscriber, the called substation will be signaled as in the usual practice; but, when a call is extended through the medium of an operator, the called subscriber will first be signaled automatically, and then the operator may re-ring the called subscriber by the use of her ringing key.

In a system of this character, it is often desired to enable the operator to re-ring the called subscriber after the automatic ring has been disconnected, either because the called subscriber has hung up his receiver before the conversation was completed or because the operator has another call waiting for the same line.

The object of my invention, therefore, is to provide an improved switching mechanism for connecting with a called line, which mechanism may be used either by a subscriber or an operator and in which means are provided for enabling the operator to re-ring the called subscriber.

In the drawings, I have shown an operator's toll selector E (Fig. 1) having access to a connector switch H (Fig. 2) which in turn has access to subscribers' lines. This connector H is also multiplied in the banks 45 of local selectors which are used when a subscriber in the same exchange desires to use the connector H.

The cord circuit C of which only a portion of the local end is shown, may be of any 50 approved long distance type and comprises among other essentials the usual tip and ring talking strands terminating in the plug P, and a ringing key K'. The calling device CD may be of any well known two wire type

such for example as the one shown in British 55 patent to Dicker No. 29,654 of 1910.

I have shown the switches in operated position, that is, in the position assumed after the call has been set up from an operator and after the called subscriber has answered, 60 to disconnect the automatic ringing circuit. To ring the called subscriber again after he has hung up his receiver is accomplished by means of the differentially wound relay 42 in the connector H and a specially tuned 65 relay 122' in the selector E. The relay 42 it will be noted, is short-circuited during the conversation to remove its resistance from the talking circuit and is also left out of the circuit when the connector H is used in 70 a local call.

I will now point out more in detail, referring to the accompanying drawings, the method of operation involved when an operator establishes a connection with the substation A (Fig. 2) automatically rings the same first and may thereafter re-ring the substation A by means of the improved circuits.

The operator first inserts the calling plug 80 P of her cord circuit into the jack X of the selector E thereby closing at the springs 2, a circuit for line relay 5 which may be traced from ground at the calling device sleeve of plug P and jack X, springs two, 85 springs 3 and 4, and relay 5 to battery. The relay 5 will immediately energize over this circuit and close a circuit for the slow relay 6 from ground through springs 8 and 9, and relay 6 to battery. The relay 5 also 90 closes a high resistance shunt about the condenser 10 which is connected between a pair of the windings of the repeating coil, said circuit extending from the upper side of condenser 10, springs 11, lower winding of 95 relay 12, and resistance 13 to the lower side of the condenser. The closure of this shunt circuit, however, has no effect at this time as the talking circuit is still open at the springs 14 and 15. The energization of the 100 slow relay 6 over the previously traced circuit supplied a ground to the supervisory circuit to light the busy lamp 16, and others which may be multiplied therewith, through springs 19 and 20; grounds the upper winding of the electropolarized relay 12, which relay, however, is arranged so that it will not operate its armatures unless the current

flowing in both windings is in the same direction, and also prepares a circuit from the back contact of relay 5 through the series slow relay 16 and the vertical magnet 5 17 at the springs 18.

- Now when the operator's calling device is operated for the first digit of the called number, the circuit of the line relay 5 is thereby interrupted a corresponding number of 10 times. Each time the relay 5 deenergizes it closes a circuit from ground through springs 8 and 21, relay 16, and vertical magnet 17 to battery. The vertical magnet 17 operates in 15 response to this series of impulses to lift the wipers 22, 23 and 24 opposite some level of the banks to which connector switches, having access to a desired group of lines, are connected. Although the circuits of relays 6 and 16 are interrupted momentarily at 20 each operation of relay 5 both will remain energized during transmission of such impulses and after the impulses cease and relay 5 comes to rest energized, the relay 16 will fall back and relay 6 will remain energized. 25 As soon as the vertical magnet operates the shaft and wipers one step, the off-normal springs 25 and 26 close. The springs 26 close the circuit of release magnet 27 at one point and the springs 25 close a point in the 30 circuit of the rotary interrupter relay 28. The circuit of the release magnet 27 is maintained open at the back contact of relay 6. The relay 28, however, energizes as soon as the springs 25 close over a circuit extending 35 from ground through springs 19 and 20 of relay 6, springs 29 and 30 of relay 16, springs 25, and relay 28 to battery. The relay 28, upon energizing, closes a locking circuit for itself at the springs 31 extending 40 from ground through springs 31, interrupter springs 32 of rotary magnet 33, springs 25, and relay 28 to battery, and also closes one point in the circuit of the rotary magnet 33 at springs 34. Now after the impulses for 45 the first digit cease and the relay 16 deenergizes, a circuit is closed for the rotary magnet extending from ground through springs 19 and 20, springs 29 and 35, springs 34, and magnet 33 to battery. The rotary magnet 50 33, therefore, operates to step the wipers 22, 23 and 24 one step onto the first set of contacts in the bank level before which it stands. Another result of the operation of the rotary magnet is to open the locking circuit of the 55 relay 28 at springs 32. The relay 28 will therefore deenergize and open the circuit of the rotary magnet at springs 34 and also open a contact in its own locking circuit at springs 31. As soon as the springs 34 open, 60 the rotary magnet will deenergize and again close springs 32. Assuming now that the trunk line selected is busy, then a ground potential will be found on the private contact with which the wiper 24 is now in contact. As soon, therefore, as the springs 32

come into contact a new circuit will be closed for the relay 28 extending from ground over the wiper 24, springs 36 and 37, springs 32, springs 25, and relay 28 to battery. The relay 28 will again operate to close the circuit 70 of magnet 33 and its own circuit to step the wipers to the next contact. This alternate operation of the relay 28 and rotary magnet 33 continues until an idle trunk line is reached, at which time no ground will be 75 found upon the private contact and the relay 28 will therefore remain deenergized after the springs 32 are closed. It may be here noted that, during the energization of the relay 16 and also during the rotation of 80 the wipers, the relay 38, although in series with the relay 28, is maintained short circuited, first by the ground through springs 19, 20, 29 and 30 and during rotation by the ground on the private wiper. The last mentioned short circuit extends from ground on wiper 24, springs 36 and 37, relay 38, springs 20 and 19 to ground. Now, however, when an idle trunk is reached, this short circuit is removed and the relay 38 which is of high 90 resistance energizes in series with relay 28. The circuit for energizing this relay extends from ground through the springs 19 and 20, relay 38, springs 32, springs 25, and relay 28 to battery. The relay 28 does not energize over this circuit on account of the high resistance of the winding of relay 38. The relay 38, upon energizing, extends the talking circuit from the windings 39 and 40 of the repeating coil to the wipers 22 and 23, 100 and also prepares a locking circuit for itself through the springs 36 and 41 which will be supplied with ground from the switch ahead as will be pointed out. Another result of the energization of relay 38 is to open the 105 springs 7, thereby preventing any further operation of the operating magnets.

Now as soon as the relay 38 closes its springs 14 and 15, a circuit is thereby established for the line relay 41 of the connector H through the windings of the differentially wound relay 42. The relay 42 does not energize at this time as its two windings oppose each other. The circuit for relays 41 and 42 extends from battery through 115 the upper winding of relay 41, springs 43 and 44, upper winding of relay 42, wiper 22, springs 14, winding 39 of the repeating coil, springs 11, lower winding of relay 12, resistance 13, which may be approximately 120 200 ohms, winding 40 of repeating coil, springs 15, wiper 23, lower winding of relay 42, springs 45 and 46, and lower winding of relay 41 to ground. The relay 12 of selector E does not energize at this time as the current in its two windings flows in opposite directions. The line relay 41, upon energizing, closes the circuit of slow relay 52 through the springs 53 and 54, which relay, upon energizing, connects ground to the re- 125 130

- lease trunk through springs 47, 122 and 121, to render the switch busy to other calls and also to supply an additional ground to the holding circuit of relay 38 (Fig. 1).
- 5 Now when the operator sends out the second digit of the called number, the line relay 5 of selector E will be operated as is the previous digit to attract and detract its armatures a predetermined number of times.
- 10 The closure of springs 8 and 21 has no effect at this time due to the springs 7 being held open by relay 38. The opening and closing of springs 11, however, opens and closes the circuit, previously traced, of the line relay 15 41 of the connector H. The relay 41, each time it detracts its armature, operates to open and close the springs 53 and 62, to thereby open and close a circuit for the vertical magnet. The circuit of the vertical 20 magnet extends from ground through springs 53 and 62, springs 56 and 57, springs 63 and 64, slow relay 69, and vertical magnet 70 to battery. The vertical magnet will be operated a number of times to step the 25 wipers 71, 72 and 73 to a group or level of trunk lines in which the terminals of the desired line are located. Upon the first vertical step of the wipers, the off-normal springs 63 and 64 are opened and spring 63 comes 30 into contact with spring 74, and the springs 75 are closed. Although the circuit for the vertical magnet is opened by the springs 63 and 64, a new circuit has been closed in the meanwhile by the operation of relay 69, 35 which circuit extends from ground through springs 53 and 62, springs 56 and 57, springs 63 and 74, springs 76 and 77, and over the previously traced circuit through the vertical magnet. It may be noted that 40 the slow relay 52 remains energized during the entire operation of the line relay regardless of the momentary deenergization thereof, and that the relay 69 remains energized constantly during the first series of 45 impulses, but deenergizes at the end of the first series when the line relay comes to rest energized. Now, when the relay 41 comes to rest energized after the impulses to the vertical magnet cease, the relay 69 will deenergize, opening its own circuit at the springs 76 and 77, and closing at the springs 76 and 78, a point in the circuit of the rotary magnet 79 and also of the slow relay 80. Now, when 50 the line relay 41 is again operated in response to the third or last digit, through the medium of the line relay 5 of selector E, the rotary magnet 79 is operated to rotate the wipers 71, 72 and 73 to the terminals of the desired line. The circuit of the rotary magnet extends from ground through springs 53 and 62, springs 56 and 57, springs 63 and 74, springs 76 and 78, springs 81, springs 82 and 83, and rotary magnet 79 to battery. A branch of this circuit extends 55 60 65 from the springs 81 through the slow relay 80 to battery so that relay 80 and magnet 79 are energized in multiple. The relay 80 energizes upon the first impulse and closes the springs 84, thereby short circuiting the springs 81 of relay 85 and maintaining the 70 circuit of itself and magnet 79 closed irrespective of the condition of relay 85 during this series of impulses. Another result of the energization of the slow relay 80 is to close a point in the 75 circuit of the busy or test relay 85, at the springs 86 and 87. The relay 80 being slow acting, will maintain the springs 86 and 87 closed for a brief interval after the line relay has come to rest and connection has 80 been made with the terminals of the desired line.
- Assuming the called line to be busy because of some call being extended therefrom, as shown, then the private contact 85 will be grounded. Before the springs 86 and 87 are opened, therefore, a circuit will be completed for the busy relay 85, extending from ground to the wiper 73, springs 86 and 87, springs 65, and relay 85 to battery. The relay 85 energizes to close a locking circuit for itself which is closed as soon as relay 80 falls back and extends through springs 65, springs 87 and 99, springs 96 and 91, springs 90 and 89, and springs 121, 90 120 and 47 to ground; opens the circuit of the relay 88 at springs 92 and 91; opens the initial energizing circuit for the rotary magnet and relay 80 at springs 81; closes a shunt or short circuit about the lower winding of 100 relay 42 at springs 97, and connects the secondary winding of the busy machine M with the lower talking conductor, thereby giving the operator a busy signal.
- The short circuit which was thus established about the lower winding of relay 42 causes said relay, whose windings are differential, to be energized, thereby switching the locking circuit of the busy relay 85 to the wiper 73, this new circuit extends from 105 ground at wiper 73, springs 98 and 90, springs 91 and 96, springs 99 and 87, springs 65, and relay 85 to battery. It will be seen therefore, that the relay 85 instead of being permanently locked, remains energized only 110 115 as long as the called line is in use and until the ground is removed from the private contact thereof.
- As soon therefore as the ground disappears from the private wiper 73, the relay 120 125 130 85 will deenergize and restore its springs to normal. The shunt being removed from the winding of relay 42 by the opening of springs 97, said relay will deenergize after a brief interval and close one point in the circuit of relay 88. The circuit for relay 88 is now complete and extends from ground through springs 47, 122 and 121, springs 89 and 90, springs 91 and 92, lower winding of relay 88, springs 90' and 86, private wiper 130

73, relay 94 of line switch C, and magnet 95 to battery. Relays 88 and 94 energize over this circuit, relay 94 being mechanically adjusted so as to attract its armatures only 5 half way when the line relay 100 is not energized, will therefore operate to disconnect the relay 100 and ground from the called line. Relay 88, upon energizing, closes a locking circuit for its upper winding through 10 springs 101, opens the circuit of relay 85 at springs 65, and places a direct ground on the wiper 73 to maintain the called line busy and also to short circuit its own lower winding. Another result of the energization 15 of relay 88 is the closure of the springs 102 and 103, thereby connecting ringing current to the called line. The ringing circuit extends from battery through the upper winding of relay 48, springs 104 and 105, 20 springs 102, wiper 71, to and through the ringer of substation A, and back through wiper 72, springs 103, springs 106 and 107, to spring 108. The spring 108 is controlled by the common interrupter relay 109 to connect 25 the above traced ringing circuit alternately to the battery B and to the generator R.

As long as the receiver of the called station remains on the hook, the ringer thereat 30 will be operated alternately and the relay 48 will remain deenergized, being non-responsive to alternating current. When the receiver is removed in response to the signal, a direct current circuit will be established 35 for said relay 48 which will immediately energize to disconnect the ringing lead from spring 108 from the circuit of the called line by opening the springs 107 and 106 and to connect the talking circuit from the condensers 110 and 111 to the wipers 71 and 72. The energization of relay 48 connects the ground from springs 112 through 40 springs 113 to close a locking circuit for its own lower winding and also connects said 45 ground to lower winding of back bridge relay 114. The springs 105 and 106, upon engaging their front contacts, close a circuit for the back bridge relay 114 extending from ground at relay 52, through springs 112, 50 springs 113, lower winding of relay 114, front contact of spring 106, springs 103, wiper 72, through the talking equipment of substation A, and back through wiper 71, springs 102, spring 105 and its front contact, and upper winding of relay 114 to 55 battery. The relay 114 energizes over this circuit and operates the springs 115 and 116 and the associated contacts to reverse the connections of line relay 41 to the talking 60 circuit, and to short circuit the windings of relay 42. This causes a reversal of current in the talking circuit to the lower winding of the back bridge relay 12 of the selector E. The relay 12 now having both windings assisting each other operates to close 65

the circuit of relay 120 at springs 121. The relay 120, upon energizing, opens the circuit of relay 122 at springs 123, closes a new circuit for the lower winding of relay 12 at springs 124, and replaces the relay 6 70 directly in the operating circuit of the operator in place of relay 5 which now deenergizes. The closure of springs 125 at this time close the circuit for a supervisory relay in the operator's cord circuit to control the 75 usual operator's signal in order to notify the operator that the called man has answered and also short circuits the relay 122. The springs 117 by the relay 114 (Fig. 2) are also closed to maintain the connector 80 relay 88 energized in case the operator should disconnect the calling plug P from the jack X before the called party has hung up, and thereby maintaining the connector in operated position, also the springs 118 85 are opened to maintain the circuit of release magnet 119 open until the called man hangs up.

Conversation may now proceed over the heavy conductors shown in the drawing and 90 when the conversation is completed, the connector may be released by either the operator or called man, that is, by the last party to restore his receiver, while the selector E is restored by the operator only. Should 95 the calling subscriber hang up first, the operator will then remove the plug from the jack X and thereby open the circuit of the relay 6 at the jack. The relay 6, upon deenergizing, closes an energizing circuit for 100 the release magnet 27 and opens the holding circuits of relays 38 and 12. The selector E is thereupon released and in releasing opens the circuit of line relay 41 of connector H. The relay 41, upon deenergizing, opens the 105 circuit of relay 52. The deenergization of these two relays prepares a circuit for the release magnet 119 which is held open at springs 118 of back bridge relay 114. Now, therefore, as soon as the called subscriber 110 hangs up his receiver, the switch will be released in the usual manner by the deenergization of relay 114 and the subsequent operation of release magnet 119. Should the called subscriber have hung up his receiver 115 first then the relay 114 would deenergize to close the springs 118 and to again operate the supervisory signal in the operator's cord circuit by means of relays 12 and 120 of selector E, after which the operator 120 would withdraw the plug to deenergize relay 41 and release the switches in the usual manner.

When the operator is calling a subscriber in the manner pointed out, it is often necessary for the operator to re-ring the called subscriber either because the called subscriber hangs up too soon or because the operator has another call waiting for the same subscriber. In this case, the operator 130

will actuate the ringing key K' to connect generator out over cord circuit and through the windings of a specially tuned relay 122' (Fig. 1). The relay 122' will not be short circuited by the springs 125 at this time, as relay 120 will be deenergized when the called subscriber hangs up. The relay 122', upon energizing, closes the springs 126 to short circuit one winding of the relays 42 and 41 (Fig. 2). This short circuit extends from ground through springs 126, winding 40 of the repeating coil, springs 15, wiper 23, lower winding of relay 42, springs 45 and 46, and lower winding of relay 41 to ground. The relay 42 being differential will energize at this time to open the springs 112, which springs control the ground connection to ring cut-off relay 48 as before pointed out. The relay 48 will therefore deenergize to again close the previously traced ringing circuit for the called station, after which, the relays are operated in the usual manner when the call is answered to disconnect the ringing circuit and again converge over the talking circuit shown.

It will be seen therefore that I have provided a very useful and efficient method by which the called subscriber may be re-rung or signaled by an operator, after the usual automatic ringing current has been disconnected and the called subscriber has again restored her receiver, and that this method is very simple and comprises only a means for again starting the automatic ring which may then be cut off by the response of the called man.

Having fully described and ascertained my invention in the foregoing specification, what I claim to be new and desire to have protected by Letters Patent will be pointed out in the appended claims.

What I claim as my invention is:

1. In a telephone system, a called line, means for establishing a connection with said called line, a source of signaling current, means for automatically connecting said source of current to the called line means for interrupting said current to intermittently operate a signal therat means for disconnecting said current, a source of alternating current, and means for applying said alternating current to said connection to actuate, means for again applying said ringing current to the called line to operate the signal before said connection is released.

2. In a telephone system, a called line, means for establishing a connection with said called line and means controlled by the called subscriber for releasing said connection, a source of signaling current, means for automatically connecting said source of current to the called line to operate a signal therat and for disconnecting said current, and manual means for again applying said

ringing current to the called line to operate the signal before said connection is released.

3. In a telephone system, an automatic switch for establishing a connection to a called line and for automatically applying signaling current thereto, means controlled by the called subscriber for releasing said connection, means in said switch for disconnecting said signaling current from the called line, and means for again causing said current to be applied to said line to signal the subscriber on said line a second time.

4. In a telephone system, an automatic switch for establishing a connection with a called line and for applying signaling current thereto to signal a subscriber on said line, means for automatically disconnecting said current when the subscriber responds to said signal, means controlled by the called subscriber for releasing the connection, and means for again applying said current to the called line without operating said releasing means after said current has been disconnected by the called subscriber.

5. In a telephone system, a pair of subscribers' lines, means for establishing a connection between said lines, and for automatically applying signaling current to the called one of said lines to signal the subscriber thereon, means controlled by the called subscriber for disconnecting said current from his line and for releasing said connection, means for preventing the called subscriber from releasing said connection, and means for again applying signaling current to the called line when the called subscriber hangs up first and before the connection has been released.

6. In a telephone system, a called line, means for establishing a connection with said line and for automatically applying signaling current thereto, a relay, an energizing circuit for said relay including said called line, means controlled by the called subscriber for closing said energizing circuit to operate said relay to disconnect said signaling current, a circuit for locking said relay energized independent of the called subscriber's control, and means for opening said locking circuit to permit said current to again be applied to said line.

7. In a telephone system, means for establishing a connection with a called line and for applying signaling current thereto, a relay for disconnecting said current from the called line, a circuit for locking said relay energized, a differential relay having contacts in series with said locking circuit, means for energizing said differential relay to open said locking circuit and again apply signaling current to said line.

8. In a telephone system, means for establishing a connection with a called line and for applying signaling current thereto, a relay for disconnecting said current from

- the called line, a circuit for locking said relay energized, a differential relay for controlling said locking circuit, a tuned relay for controlling said differential relay, and 5 means for energizing said tuned relay to energize said differential relay to in turn open said locking circuit to cause said signaling current to be again applied to said line.
- 10 9. In a telephone system, means for establishing a connection with a called line and for applying signaling current thereto, a relay for disconnecting said current from the called line, a circuit for locking said 15 relay energized, a differential relay having contacts in series with said locking circuit, means for energizing said differential relay to open said locking circuit and again apply signaling current to said line before the 20 established connection for said called line is released.
10. In a telephone system, means for establishing a connection with a called line and for applying signaling current thereto, 25 a relay for disconnecting said current from the called line, a circuit for locking said relay energized, a differential relay for controlling said locking circuit, a tuned relay for controlling said differential relay, and means 30 for energizing said tuned relay to energize said differential relay to in turn open said locking circuit to cause said signaling current to be again applied to said line before the established connection with said called 35 line is released.
11. In a telephone system, an operator's position, a subscriber's line, means controlled by the operator for establishing a connection with said line and for automatically 40 applying ringing current thereto, a relay for automatically disconnecting said ringing current from the called line, a circuit for locking said relay energized, a differential relay for controlling said locking circuit, a tuned 45 relay for controlling said differential relay, and means controlled by the operator for supplying alternating current to said tuned relay to energize the same, to thereby energize said differential relay to open said locking 50 circuit and cause ringing current to again be applied to the subscriber's line.
12. In a telephone system, an operator's position, a subscriber's line, means controlled by the operator for establishing a 55 connection with said line and for automatically applying ringing current thereto, a relay for automatically disconnecting said ringing current from the called line, a circuit for locking said relay energized, a differential 60 relay for controlling said locking circuit, a tuned relay for controlling said differential relay, and means controlled by the operator for supplying alternating current to said tuned relay to energize the 65 same, to thereby energize said differential
- relay to open said locking circuit and cause ringing current to again be applied to the subscriber's line before the connection to the subscriber's line is released.
13. In a telephone system, an operator's 70 position, a subscriber's line, means controlled by the operator for establishing a connection with said line and for automatically applying ringing current thereto, a relay for automatically disconnecting said ringing 75 current from the called line, a circuit for locking said relay energized, a double wound relay for controlling said locking circuit, a relay for controlling said double wound relay, and means controlled by the operator 80 for energizing said last mentioned relay to energize said double wound relay by short circuiting one of its windings whereby the locking circuit of said first relay is opened and ringing current is again applied to the 85 subscriber's line.
14. In a telephone system, an operator's position, a source of signaling current, means controlled by operator for establishing a connection to a called line and for 90 automatically applying said signalling current thereto, said current being automatically cut off by the response of the called subscriber, a relay, a source of alternating current, means for preventing the release of 95 the connection upon the subsequent hanging up of the receiver at the called station and for preventing said signalling current from being again applied to the called line upon the said restoration of the called subscriber's 100 receiver, and means controlled by the operator for applying said alternating current to said connection to actuate means for again applying said first current to said called line before the connection is released. 105
15. In a telephone system, a called line, means for establishing a connection with said line, two sources of alternating current, a relay, means for automatically connecting one of said sources of current to said called 110 line to operate a signal thereat, means for disconnecting said current, and means for applying said second source of current to said relay to again apply said first mentioned ringing current to said called line. 115
16. In a telephone system, an operator's position, a called line, means for establishing a connection with said line, two sources of alternating current, a relay, means for automatically connecting one of said sources 120 of current to said called line to operate a signal thereat, means for disconnecting said current, and means under the control of the operator for applying said second source of current to said relay to again apply said first 125 mentioned ringing current to said called line.
17. In a telephone system, a telephone line, means for establishing a connection with said line, a source of signalling current, 130

- means for automatically connecting said source of current to said line to operate a signal thereat, means for disconnecting said source upon the response of the subscriber 5 on said line, a source of alternating current, and means for applying said alternating current to said connection to again actuate said means for connecting said source of signalling current to said line.
- 10 18. In a telephone system, a telephone line, an automatic switch for establishing connection with said line, a source of signalling current, means in said switch for automatically connecting said source of current to said line, means actuated by the response of the subscriber on the said line for disconnecting said source of ringing current, a source of alternating current, and means for connecting said alternating current to 15 said connection to actuate automatic means for again connecting said source of ringing current to said line.
19. In a telephone system, an operator's position, an automatic switch, telephone lines 20 accessible to said switch, means controlled by the operator at said position for operating said switch into connection with one of said lines, a source of ringing current, means in said switch for connecting 25 said source of ringing current to said line, automatic means operated upon the response of the subscriber on the connected line for disconnecting said ringing current, a source of alternating current, and means for connecting said source of alternating current to said connection to cause said source of ringing current to be again connected to the connected telephone line.
20. In a telephone system, an operator's 40 position, an automatic switch, telephone lines
- accessible to said switch, means controlled by the operator at said position for operating said switch into connection with one of said lines, a source of ringing current, means in said switch for connecting said source of ringing current to said line, automatic means in said switch operated upon the response of the subscriber on the connected line for disconnecting said ringing current, a source of alternating current and 45 a key at said operator's position for connecting said source of alternating current to said connection to cause said source of ringing current to be again connected to the said connected line. 50
21. In a telephone system, a called line, means for establishing a connection with said line, a source of signalling current, means for automatically connecting said source of current to said called line to operate a signal 55 thereat, means for disconnecting said current, a source of alternating current, and means for connecting said source of alternating current to said connection to again apply said ringing current to said line. 60
22. In a telephone system, a called line, means for establishing a connection with said line, a source of signalling current, a relay, means for automatically connecting said source of current to said called line to 65 operate a signal thereat, means for disconnecting said current, a source of alternating current, and means for applying said source of alternating current to said relay to again apply said signalling current to 70 said called line.

Signed by me at Chicago, Cook County, Illinois, this 26th day of February, 1918.

JOHN WICKS.
